B. COHEN

AWNING CONSTRUCTION

Filed April 2, 1928

INVENTOR
Benjamin Cohen.
BY
Louis Barnett.
ATTORNEY

UNITED STATES PATENT OFFICE.

BENJAMIN COHEN, OF BROOKLYN, NEW YORK.

AWNNG CONSTRUCTION.

Application filed April 2, 1928. Serial No. 266,537.

This invention relates to window awnings, canopies and the like structures. More particularly the invention is directed to improved awning constructions, the cover or canvas of which may be readily applied and stretched or removed from a supporting structure or framework.

One object of the invention is to provide in a device of the character described, a fabric cover or canvas formed with a pocket of novel construction for receiving the usual shape-retaining and supporting frame, said improved pocket construction including suitable closure means such as hookless fasteners for releasably retaining the canvas to said frame.

Another object of the invention is to provide in a device of the character described, a cover or canvas formed with improved quick detachable means, such as hookless fasteners adapted to permit removably applying the cover or canvas to supporting and stretching frame members of awnings, canopies or the like structures already installed without modifying or altering such structures.

A further object of the invention is to provide an improved device of the character described comprising few and simple parts, including a cover or canvas which shall be easily and quickly applied in position on a frame structure or removed therefrom for storage eliminating the requirement of trained or skilled labor, which shall be relatively inexpensive yet form a rugged, neat appearing structure, and which shall be practical and efficient to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claims.

In the accompanying drawing, in which is shown various possible illustrative embodiments of this invention,

Fig. 1 is a perspective view of a window opening with an awning embodying the invention applied thereto.

Fig. 2 is a fragmentary plan view of a

cover or canvas of the improved awning laid flat to show the underside construction.

Figs. 3, 4 and 5 are cross-sectional views taken on lines 3-3, 4-4 and 5-5, respectively, in Fig. 1, and

60

Fig. 6 is a fragmentary plan view of a modified construction of a cover or canvas of the improved awning laid flat to show the underside thereof.

This invention is not only applicable to new awnings, canopies and other like structures but may also be incorporated in structures already installed to replace or permit quick interchanging of the cover or canvas thereof. An embodiment of the invention 70 is here shown applied to a window awning.

Referring in detail to the drawing, 10 denotes the improved awning embodying the invention shown in Fig. 1, installed to shade an upper portion of a window opening 11 75 provided in a building wall 12. Said awning is seen to comprise a U-shaped supporting and stretching frame or bail 13 for a novelly constructed cover or canvas 14.

The frame 13 may be of any well understood construction and is preferably made of a bent metallic rod or pipe of circular cross-section, the free ends of said frame terminating in eye-fittings 15 which are either integrally formed with said ends or are rigidly mounted thereon. Each fitting 15 extends between the bifurcated portions 16 of an attachment member 16 and is swingably connected thereto by suitable means such as a pin 17 and retaining cotter 18. Said member 16 is firmly mounted on the building wall 12 at the exterior, opposite upright trim members 11^a surrounding the window opening 11 thus pivotally supporting the frame 13 in the well understood manner.

The cover 14 may be made of a suitable material such as canvas, duck or other water-proofed textile or silk fabric properly cut, fashioned and fabricated, to a desired shape for shading window opening 11. Said cover 14, as seen in Fig. 2 comprises a main panel 19 and two identical triangular-shaped side panels 20 which are secured to opposite sides of the main panel by seams 21. If desired an apron or border flounce 22 may

100

be stitched to extend along the lower edge portions 19^a and 20^a of the panels 19 and 20, respectively. The upper edge portion 19^b of the panel 19 has a corded hem 23 on 110

which is permanently secured spaced staple loops 24. The latter are adapted to releasably interlock with spaced anchoring screw-eyes or hooks 25 provided along the upper 5 horizontally extending trim member 11^b of the window frame, as is clearly shown in Fig. 1.

To stretch and support the cover 14 on the frame 13, a pocket 30 for receiving the latter is provided to extend along the lower edge portions 19^a and 20^a on the under sides of the panel 19 and 20, respectively. Said pocket preferably is constructed by inturning a portion of said edge portions 19^a and 20^a to form inner flap pocket walls 30^a and 30^b, respectively, thus permitting the quick and easy insertion of the frame 13 into the pocket.

For retaining the frame 13 in the pocket suitable quick-releasably closure fastener means 31, such as the so-called "hookless fastener" are provided for securing the free edge of the flap pocket walls 30^a and 30^b to the adjacent portions of the panels 19 and 20, respectively. The hookless fastener 31 may be incorporated in the cover in a single continuous length extending successively through each of the panels but is preferably provided in a plurality of sections so that if a portion of the fastener 31 should accidentally become defective only that section need be replaced. A two sectional construction is shown in Fig. 6 and a section for each panel is shown in Fig. 2.

35 In each of the constructions described above the cooperative portions 31^a and 31^b of the hookless fastener means 31 are sewed in position, one portion 31^a along the free edges of pocket flap walls 30^a and 30^b and the other portion 31^b on the panel portions 19^a and 20^a, sliders 31^c interlocking and releasing the conjunctive edges of said cooperative portions 31^a and 31^b in the well understood manner.

45 The blind ends 31^d of said hookless fastener means are positioned adjacent the outer ends of the pocket flap walls inwardly of the edge portions 20^c of the panels 20. Said portions 20^c preferably are each reinforced by an extra thickness of material and provided with a grommet 32 which is adapted to be anchored by passing the pin 17 therethrough as shown in Figs. 1 and 4.

55 Suitable means for raising and lowering the awning are provided in the form of one or more hand ropes 33 passing over suitable pulleys 34 which are secured to the trim member 11^b below the aligned hooks 25. Each rope 33 has a portion thread through 60 spaced and aligned guiding rings 35 which are stitched to the under sides of the panel 20, and has its end secured to the portion of the frame 13 extending through the pocket in the main panel. The rope may either 65 be looped and tied around said frame por-

tion as shown at 40 or an extra reinforcing band 37 may be incorporated in the pocket structure as shown in Fig. 2.

When the end of the rope is looped and tied, small passages 38 and 39 are provided 70 between the main panel 19 and the hookless fastener portion 31^b and between the pocket wall 20^b and the fastener portion 31^a, respectively, so as not to interfere with the operation of said fastener sliders 31. 75

Where the band 37 is used for anchoring the rope end, the ends 37^a of the band 37 are extended back of the hookless fastener portion 31^b and in front of the portion 31^a as seen in Fig. 2, and have grommets 38 to 80 form anchoring tabs for the end of the rope. Said band is preferably stitched in position to reinforce the pocket wall structure.

The application of the invention will now be apparent. A cover 14 of the proper size 85 and shape is constructed as described above and assembled with the frame 13, and the rope control over the window opening 11 in the usual manner. The frame 13 is attached to the cover 14 for stretching and 90 retaining the shape of the awning by simply inserting the frame in the pocket 30 with the pocket flap walls 30^a and 30^b released by the hookless fastener means, each end of the frame being inserted into the secured 95 portion of the pocket wall at the blind ends 31^d prior to attaching said frame ends to the attachment member 16. The sliders 31^c are then moved to close the pockets 30 thus securing the cover 14 to the frame 13. 100

To remove the cover, the sliders are moved to open the pockets 30 and the frame 13 removed after first detaching the ends thereof from the member 16. The remaining devices securing the cover to the building are 105 released in the well understood manner.

In the above described construction the frame is secured and concealed by the cover forming a rugged yet neat appearing structure.

110 It will thus be seen that there is provided a device in which the several objects of this invention are achieved and which is well adapted to meet the conditions of practical use.

115 As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:—

120 1. A device of the character described adapted to extend from a building over an opening therein comprising, a cover having a pocket formed along an edge portion there- 125 130

of, adapted to enclose a stretching frame, and a hookless closure fastener means incorporated to extend throughout the length of said pocket structure to facilitate the assembly and dismounting of the cover from the frame.

2. An awning comprising a cover, detachable fastening means mounted along one edge of the cover adapted to secure the latter to a building above an opening therein, a pocket formed along an edge portion of the inner side of the cover opposite to said detachable fastening means, said pocket being adapted to enclose a stretching frame connected to a rim portion of said building opening, and a hookless fastener incorporated to extend throughout the length of the pocket structure to facilitate the insertion and removal of the cover from the frame.

3. In an awning construction, a cover having a pocket extending along an edge portion thereof adapted to enclose a supporting and stretching frame, the structure of the pocket incorporating a hookless fastener extending throughout the length thereof which serves as a releasable closure means for the pocket to permit the ready insertion and removal of the cover from the frame.

4. A window construction comprising a cover having detachable fastening means extending along one edge portion thereof

adapted to secure the cover over an opening of a building, another edge portion of the cover formed with a pocket adapted to enclose a swinging bail pivotally mounted to a rim portion of said opening for supporting and stretching the cover, a hookless fastening closure means incorporated in the pocket structure to facilitate the insertion and removal of the cover from the bail, and a control rope for collapsing the awning, one end of said rope connecting with said bail within the pocket.

5. A window construction comprising a cover having detachable fastening means extending along one edge portion thereof adapted to secure the cover over an opening of a building, another edge portion of the cover formed with a pocket adapted to enclose a swinging bail pivotally mounted to a rim portion of said opening for supporting and stretching the cover, a hookless fastening closure means incorporated in the pocket structure to facilitate the insertion and removal of the cover from the bail, a looped band adapted to engage the bail within the pocket, the ends of said band extending beyond the pocket, and a control rope for collapsing the awning having one end secured to said band ends.

In testimony whereof I affix my signature.

BENJAMIN COHEN.
